DESIGN FOR A TEETHING RING

Harry L. Youngquist, San Antonio, Tex.

Application April 21, 1944, Serial No. 113,333

Term of patent 14 years

(Cl. D83—1)

To all whom it may concern:

Be it known that I, Harry L. Youngquist, a citizen of the United States, residing at San Antonio, in the county of Bexar and State of Texas, have invented a new, original, and ornamental Design for Teething Ring, of which the following is a specification, reference being had to the accompanying drawing, forming part thereof.

In the drawing:

Fig. 1 is a front elevational view of a teeth-

ing ring showing my new design, the back view being of similar appearance;

Fig. 2 is an edge view thereof; and

Fig. 3 is an enlarged transverse cross-sectional view taken on a horizontal plane through the center of the teething ring in Fig. 1.

I claim:

The ornamental design for a teething ring, as shown and described.

HARRY L. YOUNGQUIST.
